United States Patent Office.

JAMES HARRISON, OF NEW YORK N. Y.

Letters Patent No. 67,537, dated August 6, 1867.

IMPROVED MODE OF RINGING BELLS.

The Schedule referred to in these Letters Patent and making part of the same.

TO ALL WHOM IT MAY CONCERN:

Be it known that I, JAMES HARRISON, of the city of New York, in the county and State of New York, have invented a new and useful Mode of Mounting Bells; and I do hereby declare that the following is a full, clear, and exact description of the construction and operation of the same, reference being had to the annexed two sheets of drawings, making a part of this specification, in which—

Figure 1, on sheet 1, is a perspective view of the bell and mountings, complete.

Figure 2, on sheet 1, is a top view, showing the combination of lever *m* and cam *k*, with the working pawl *J''* working into ratchet-wheel *H*, and gear-wheel *I* working into gear-wheel *g*, and gear-wheel *F* working into gear-wheel *e*, and screw or worm-wheel *d* working into the large gear-wheel *C*.

Figure 3 shows cam *k*, with lever *m*.

Figure 4 the joint in which it works.

Figure 5 shows the working lever *J*, with the working pawl *J''*.

Figure 6 the check-spring *s*.

Figure 7, on sheet 1, is a perspective view of a bell, with a piece broken out, in order to show the application of the same combination of gears applied to the hammer inside the bell instead of outside the bell, as shown in fig. 1.

Figure 8 is a front view of ratchet-wheel *g*, and gear-wheel *F* working into gear-wheel *d*, and screw gear-wheel *e* working into large gear-wheel *D*, as shown in fig. 7. The swinging of the hammer from one side of the bell to the other gives a backward and forward motion to the working pawl *I*, which causes the ratchet-wheel *g* to move round forward, and is prevented from moving backward by the check-dog *J'*; thus the continued swinging of the hammer effects the rotation of the clevis *c* to which the clapper is connected.

Figure 9 is intended to show the yoke *B*, with a little different combination of gear-wheels, arranged horizontally, as shown, and set in motion by the action of cam or eccentric *k*, and pawl *J''* working into ratchet wheel *I*. The bell is made fast to the gear-wheel *C*, as shown in fig. 1.

Figure 1, on sheet 2, is a perspective view of bell and mountings, complete, same as fig. 1 on sheet 1, only showing a less combination of gear-wheels, intended only for small bells.

The figures from No. 2 to No. 13, on sheet 2, are intended to show parts of fig. 1 on sheet 1 and of fig. 1 on sheet 2, the same being applicable to both.

Figures 2 and 3 are nuts.

Figures 4 and 5 are washers.

Figure 6 is the middle portion of yoke *B*, in which is cast the round hole *m'* part way through the yoke *B* and the square hole *n* through the top part of yoke *B*.

Figure 7 shows the yoke *B* cut in two, in order to show the relative position of the round hole *m'* and the square hole *n* in the middle of yoke *B*.

Figures 8 and 9 are washers.

Figure 10 is a gear-wheel, *D*, with a projecting socket, *r*, to fit on the projection *T* on top of the bell.

Figure 11 shows the gear-wheel *D* on fig. 10 cut in two, in order to show the relative position of socket *r* with centre hole *s* through hub *D''*.

Figure 12 shows the top of the bell, with a square projection, *T*, to fit into socket *r* on gear-wheel *D*. In large bells this projection is made round, and in that case the socket on gear-wheel *D* will be round also.

Figure 13 is the bolt *o n'* that holds the bell to the yoke, and the clapper *Y* on this bolt *o n'* is a square collar, *n''*, which is made to fit into the square hole *n* in middle of yoke *B*, and by this means prevent the clapper from turning round with the bell, and always keeping it at right angles with the bell.

Figure 14 is a perspective view of a bell mounted, with a ratchet motion fixed at the joint of the hammer, so that the action of the hammer in moving to and from the bell will cause the working pawl *I'* to drop into a new tooth on the ratchet-wheel *B'* at every motion of the hammer, thus causing the hammer to rotate round the outside of the bell.

Figure 15 is an end view, and

Figure 16 a side view, in order to show those parts that cannot be seen in fig. 14.

To enable others skilled in the art to make and use my invention, I will now describe its construction and operation.

Letter A in fig. 1, sheet 1, is the bell, B the yoke, C the gear-wheel on top of the bell, d the worm or screw-gear, e a small gear-wheel, F a small gear-wheel, g a large gear-wheel, H a large ratchet-wheel, I a small gear-wheel; J'' is the working pawl, k the cam or eccentric, m the lever, l the joint in which the cam-lever works; n''' is a chain or cord fastened from the end of cam-lever m to the arm of the tolling-hammer o'; P is the rope fastened in the end of arm of tolling-hammer and conveyed down to the bell-ringer's room; q q are the standards that bear the weight of the bell; R is the clapper. The bell is first made with a projection or top, of any desired form or shape, like fig. 12 on sheet 2. The gear-wheel D on fig. 10, sheet 2, is then made, with a hole or socket on the under side to fit the projection T on top of the bell. This wheel also has a projecting hub on top, D'' in fig. 11, that fits into the round hole in middle of yoke B, fig. 6, sheet 2. The bolt o n' on fig. 13 is then put through the top of the bell T and the gear-wheel D', and the hub D'' and the yoke B, until the square collar n'' comes into the square hole n in the middle of yoke B, as shown in figs. 6 and 7 on sheet 2. The nuts are then screwed on to the end of bolt o n', and the bell is made fast to the yoke B. The worm or screw-wheel d and gear-wheel e are then put in the position as shown in figs. 1 and 2 on sheet 1, so that the thread of worm-wheel d will work into the gear-wheel C. The gear-wheels F g are then put into the yoke B, so that the teeth of gear-wheel F will work into gear-wheel e. The ratchet-wheel H and gear-wheel I are then put into the yoke B, so that the teeth of gear-wheel I will work into the gear-wheel g. The cam k is then put into the joint b on stand q. The working lever J and working pawl J'' are then put into the yoke B, and on the same bolt with ratchet-wheel H, the end of lever J resting on cam k. The check-spring s is then put to work into ratchet-wheel H. The tolling-hammer o is then put into the stand q, and the chain or rope n''' is then attached from the lever m of cam k to the arm of tolling-hammer o'. The rope P is then attached to arm of tolling-hammer o'. The bell is then mounted.

The operation is as follows: In swinging the bell to and fro, in order that the clapper R shall strike the side of the bell, the end of lever J moves up and down the eccentric cam k, thus giving to the working pawl J'' a motion up and down the ratchet-wheel H, so that as it goes down it falls into a fresh tooth in ratchet-wheel H, and as it goes up, it moves ratchet-wheel H one tooth forward, and check-spring s slips into ratchet-wheel H and holds it there. Thus, by the action of swinging the bell, it is made to rotate horizontally around its own centre. In cases where the bell is large, and where it is used daily for morning services, they do not swing the bell as above described, but they use the tolling-hammer o', which is applied to the bell mountings for that purpose; and in order that the bell shall be rotated horizontally around its own centre by the action of the tolling-hammer I have constructed the eccentric cam k, fig. 3, sheet 1, with the attached lever m working in joint l, fig. 4, and have attached the lever m to the tolling-hammer o' by chain or rope n''', as shown in fig. 1, sheet 1, so that when the ringer pulls down on rope P he will also pull down the chain or rope n''' and the lever m, thereby lifting up cam k and working pawl J'' the distance of one tooth and moving the ratchet-wheel H, the check-spring s slips into ratchet-wheel H and keeps it there. When the ringer lets the tolling-hammer o' fall back to strike the second blow, the working pawl J'' moves into another tooth on ratchet-wheel H, and so, by the action of the tolling-hammer, the bell is made to rotate horizontally around its own centre. The addition of a single rope tied to the end of lever m or cam k, and carried down to the bell-ringer's room, will enable him to rotate the bell, independent of the action of swinging the bell or of the use of the tolling-hammer, by giving to the said rope an up-and-down motion, causing the cam k to move up and down, thereby working the ratchet H, as before described. This is sometimes necessary when we remount old bells that have been in use a long time, and have been incessantly struck on two points until the metal at those points has worn very thin and brittle, so that a few blows more would break the bell. In this case the bell-ringer would use the extra rope and rotate the bell, without striking or sounding the bell until it had passed the point of danger. The lever J is forked, so that it embraces ratchet-wheel H, and the end of each fork is connected with the bolt or axis of said ratchet-wheel H. The cam k is permanently secured to lever m, so as to partake of whatever motion is given to said lever m. The lower or under side of said cam is hollowed out to form a socket, which fits a fixed pin or rest that projects from the inner face of standard q. Said pin or rest is seen in the drawing in fig. 1, sheet 1, partly covered and concealed by the cam. When the lever m is in its normal position, the cam k rests upon said pin so as to have a firm bearing thereon; and the said cam is held stationary and prevented from having any movement sideways, because the sides of the cam project on each side of the pin. This arrangement enables me to use the said cam for rotating the bell by the swinging of the bell itself, the lever J, which carries pawl J'', being above the axis on which the yoke B turns, the swinging of the bell and yoke carrying the free end of lever J (whose end is provided with an anti-friction roller) to and fro over the top of cam k, whereby said free end of that lever is lifted and the pawl J'' is operated, as above explained. In rotating the bell through the swinging of the clapper, the lever m is vibrated and the cam k is brought up against the end of lever J, which is lifted so as to operate the pawl, the curve on the top of cam k being reduced or flattened at the point where the end of lever J or the anti-friction roller rests, so that the parts will not roll or move away from each other.

What I claim as new, and desire to secure by Letters Patent, is—

1. The combination of the lever m and cam or eccentric k, substantially as and for the purpose described.
2. Arranging a pin or rest beneath cam k to support it and give it a firm bearing, and also curving the under side of the cam, substantially as described.
3. The combination and arrangement of the movable cam or eccentric k with the pawl lever J, substantially as described.

4. The combination of the movable cam or eccentric *k*, lever *m*, and clapper *o'*, substantially as described, for the purpose of rotating the bell.
5. The combination of the movable cam or eccentric *k* and pawl lever *J* with the gearing *H*, *I*, *g*, *F*, *e*, worm *d*, and wheel *C*, substantially as and for the purpose described.
6. The arrangement in yoke *B* of square hole *n* in the centre of round hole *m'*, for the purpose of receiving the square part *n''* of bolt *o n'*, substantially as described.

JAMES HARRISON.
